UNITED STATES PATENT OFFICE.

LESLIE R. McDONALD, OF MONTREAL, QUEBEC, CANADA.

DISPLAY APPARATUS.

Application filed April 1, 1924. Serial No. 703,386.

To all whom it may concern:

Be it known that I, LESLIE R. McDONALD, a citizen of the United States, residing at Montreal, Province of Quebec, Dominion of 5 Canada, have invented certain new and useful Improvements in Display Apparatus, of which the following is a specification.

My invention relates to that class of display apparatuses wherein a plurality of 10 placards are successively brought into view position; and my improvements are directed particularly to the construction of such an apparatus wherein a considerable number of 15 independent and disconnected placards may be exhibited one by one, successively carried away from view position, reversed, and the 20 reversed side exhibited. An important object of my invention is to construct an apparatus wherein the placards, consisting of single sheets of pasteboard or the like, may 25 be exhibited, as above suggested, without attaching them definitely to the carrying apparatus, so that cards which have been cut of the proper size and form may be placed 30 loosely and disconnectedly in the apparatus and successively exhibited by it one by one; another object of my invention is to produce 35 novel and improved means for withdrawing the placards from view position and for reversing and carrying them forward again.

Still another object of my invention is to provide means for preventing injury to the 40 placards when they are brought down from above into view position one by one. And still another object of my invention is to provide means whereby the last placard may be 45 separated from those preceding it and moved into view position without disarranging the other placards.

The means by which I obtain these and other objects of my invention will be set forth and explained in the following specification.

In the drawings Fig. 1 is a front elevation 45 of an apparatus embodying my improvements; Fig. 2 is a similar view with the case shown in section; Fig. 3 is a side view, taken on the line 3—3 of Fig. 2, looking to the right; Fig. 4 is a vertical section, taken on the line 4—4 of Fig. 1, looking to the right; Fig. 5 is a plan view of the mechanism for receiving and moving the placards from front to rear and for initiating the movement of each placard successively toward 50 view position; Fig. 6 is a view, taken on the line 6—6 of Fig. 5, looking to the left, the

driving mechanism being omitted for clearness; Figs. 5 and 6 are on an enlarged scale; Fig. 7 is a partial rear elevation on an enlarged scale; Fig. 8 is an elevation on an enlarged scale of the card shifting mechanism of a modification, a medial part of the mechanism being omitted for the purpose of shortening the figure; and Fig. 9 is an end view of the modification, taken as looking to the right on Fig. 8.

In all the figures similar parts are designated by similar reference numerals.

The apparatus is preferably arranged in a case 1, provided with a suitable open or glazed front 2; and the operative parts of the apparatus are assembled upon a suitable framework 3 adapted to support the various parts in proper relation, or supported directly by the base of the case. Operative 70 power may be furnished by a motor 4, the shaft 5 of which carries a worm 6 meshing with a worm gear 7 keyed to a shaft 8 rotating in suitable bearings in the end of the frame 3.

Fixed upon the shaft 8 is a sprocket wheel 9, the teeth of which engage with a chain 10 traveling around the sprocket wheels 11 and 12, respectively attached to shafts 13 and 14 journalled in the framework of the machine 80 and carrying respectively rollers 15, 16. The shaft 13 also carries a gear 17 meshing with a gear 18 on a shaft 19 also journalled in the frame and carrying a roller 20; and the shaft 14 also carries a gear 21 meshing with 90 a gear 22 on a shaft 23 also journalled in the frame and carrying a roller 24.

Also pivoted in the ends of the frame and extending across the apparatus are rollers 30, 31, 32, 33, 34, 35 and 36, which turn freely 95 on their bearings in the framework, the rollers 30 and 31 being preferably provided with means, illustrated as consisting of annular flanges 37, to prevent the shifting of the belts which travel around the rollers.

Belts 40, 41, 42 are carried around the rollers 15 and 16 and over the rollers 20, 32, 33, 34, 35, 36, 24, 31 and 30, so that the rotation of the rollers 15 and 16 will cause the belts 100 to travel over the rollers in the path indicated in Fig. 4.

The shaft 8 also carries a sprocket wheel 45 serving to drive a chain 46, meshing with a sprocket wheel 47 on a shaft 48, journalled in the lower part of the apparatus 110 and carrying bevelled gears 49, 50, meshing, respectively, with gears 51 and 52 car-

ried by shafts 53 and 54 disposed in suitable bearings transversely of the apparatus. The shaft 53 carries a worm 55, one end of which is slightly expanded as at 57, and the pitch of the worm groove being increased and the worm groove continued around the eccentric 59; and the shaft 54 carries a similar worm 56, which is provided with a similar taper 58 and a similar eccentric 60, the pitch of the thread, however, on the worm and eccentric being reversed from that of the thread on the worm 55. The ends of the shafts 53 and 54 are provided with annular flanges 61, 62 having bevels 63, 64 adjacent to the grooves of their respective worms 55 and 56. Beyond these flanges shafts 53 and 54 are carried through suitable bearings 65, 66 and are provided respectively with cams 67, 68, against which bear 10 ends 69 and 70 of a cross bar 71, attached to a flange 72 of the spring plate 73 secured at the bottom of the apparatus and having its upper, free end provided with fingers 75, 76 normally projecting through apertures in an inclined card guide 77, but adapted to be withdrawn by springing back of the plate 73 under the influence of the cams 67, 68.

In the ends of the apparatus are placed 30 card guides 79, 80, adapted to engage the ends of the card and direct them in their descent into view position.

Between the worms 55 and 56 is placed a card detent 83, which has an expanded and 35 rearwardly tapered head 84 disposed in a plane slightly above the worms 55 and 56, its rear end terminating just in advance of the axial line of the faces of the eccentrics 59 and 60.

40 Placards 90—90 of cardboard, or similar flexible material, are provided at their tops and bottoms with dovetailed notches 91, adapted to straddle and slide along the detent 83, but not to be released therefrom 45 until they reach its inner end, thus holding down the cards as they approach the rear of the apparatus, until the last one is in position to be raised and carried forward again. The upper portion of the last card rests 50 upon a suitable support, such as a roller 95, journaled in the ends of the apparatus and disposed in line with the top of the eccentrics 59 and 60 and the adjoining faces of the rollers 15 and 20; and owing to the 55 fact that the support 95 and the meeting faces of the rollers 15 and 20 are set back of the plane of the eccentrics 59 and 60 and the fact that the bottoms of the cards are separated one from another by the worms 60 55 and 56, the cards will normally tend to slant backward so that the pack will normally bear against the roller or support 95.

In the drawings the thickness of the cards and the width of the worm thread have been 65 increased, for clearness, substantially above

the proportions permissible for use in actual practice; with the result that the number of cards shown in the illustration is considerably less than what may be used in a full sized operating machine.

In practice it has been found that shafts of three quarters ($\frac{3}{4}$) or seven eighths ($\frac{7}{8}$) of an inch diameter and thread of sixteen (16) turns to the inch may be used, it being preferable, however, to gradually about 75 double the pitch of the thread over the last few turns before it merges with the cam, as this will permit a better separation of the lower edges of the cards and give a better control over the cards by the mechanism 80 which controls their successive elevation.

In Figs. 8 and 9 I have illustrated a modification of the card forwarding mechanism, a single large roller 100 being substituted for the five small rollers 32, 33, 34, 35 and 36, 85 and another roller 101 being substituted for the two rollers 30 and 31; and instead of the belts 40, 41 and 42 I employ in the modification an endless cord 102, which is carried around the rollers 15, 100, 16, 101 and across 90 the apparatus over guide pulleys 103 and 104, one or both of the rollers 15 and 16 being preferably provided with grooves 105 to assist in guiding the cord as it travels around the rollers.

This modified form of apparatus will 95 efficiently handle the cards; but it requires a higher casing than the form which I first described, and is, therefore, not as economical of space as the other form. If the modified form of apparatus is used the worm gear 7 may be mounted directly on the shaft 105 of the roller 100, and the driving mechanism for the rollers 15 and 16 may be omitted as the traction of the roller 100 will be sufficient to operate all the rollers in the system covered by the cord 102.

The operation of my apparatus is as follows.

The apparatus having been furnished, preferably with a full set of cards, the motor is started and the following cycle of operation takes place. The card at the back of the apparatus and which is resting against the support 95, is raised by the worm groove in the rotating eccentrics 59 and 60, sliding up above the next card until its upper edge is gripped between the belts 40, 41, 42 and the roller 20, which then draw the card upward and feed it forward between the belts and the rollers 33, 34, 35, 36 and 24, and discharge it downward behind the open front of the case. As the card descends its lower edge strikes the guides 79 and 80 and is directed inwardly and downwardly to the inclined face of the guide 77, along which it slides until arrested by the fingers 75 and 76 projecting through the guide 77. Meanwhile, 130

the pack of cards has been moved backward on the worms, and the bottoms of the last few cards being separated more widely by the increased pitch of the worm groove, the last card slipping off the end of the card detent 83 and being free to be raised in its turn by the eccentrics 59 and 60.

This movement of the cards makes room for the card which has just been transferred from the rear to the front of the apparatus and is being held up on the fingers 75 and 76.

The rotation of the cams 67 and 68 presses down the cross bar 71 and springs forward the plate 73, withdrawing the fingers 75 and 76 from beneath the card, which then slides down upon the bevelled faces of the flanges 61 and 62 and seats itself in the worm grooves to be carried to the back 20 of the machine in its turn.

The receiving of the card, when it has dropped from above, by the guide 77 and the fingers 75 and 76 has the effect of being arrested gradually so that it does not fall with its full weight and directly upon the worms, but is let down to them gently, so as not to bruise or injure the card, and at the proper time to take up its backward travel under the influence of the worm groove.

It will be noted that this operation reverses the card each time that it is transferred from rear to front, thereby exhibiting both of its sides for advertising purposes and practically doubling the publishing capacity of the apparatus.

Furthermore, the direction in which the card will be bent in being transferred from rear to front will be reversed with each transference; thereby avoiding the giving of a permanent set or bend to the cards, which might interfere with their normal positioning in the apparatus.

I desire it to be understood that the embodiments of my invention which I have shown and explained are to be considered as illustrative and not as exclusive types; for obviously details of construction may be modified, as by the use of mechanical equivalents, without departing from the spirit of my invention as described and claimed.

Having thus described my invention, what I claim and desire to secure by Letters Patent of the United States, is:—

1. In a display apparatus, the combination of a plurality of independent, flexible placards, with supporting and shifting means embodying a pair of worms each having an enlarged end and placard transferring means.

2. In a display apparatus, the combination of a plurality of independent, flexible placards, with supporting and shifting means embodying a pair of worms embody-

ing a worm having a helical and eccentrically disposed terminal thread and placard transferring means.

3. In a display apparatus, the combination of a plurality of independent, flexible placards, with supporting and shifting means embodying a pair of worms of opposed pitches each worm having a helical, eccentric terminal, and placard transferring means. 75

4. In a display apparatus, the combination of plurality of independent, flexible placards, with supporting and shifting means, placard detaining means adapted to engage with the lower portions of the placards, means for initiating the separation of the placards successively, and placard transferring and reversing means. 80

5. In a display apparatus, the combination of a plurality of independent, flexible placards, with supporting and shifting means, means for engaging with and holding down the bottom of the next to the last placard, means for initiating the separation of the placards successively, and placard transferring and reversing means. 85

6. In a display apparatus, the combination of a plurality of independent, flexible placards, with supporting and shifting means, means for engaging with and holding down the bottom of the next to the last but not the last placard, means for initiating the separation of the placards successively, and placard transferring and reversing means. 90

7. In a display apparatus, the combination of a plurality of independent, flexible placards each provided with a marginal recess, with supporting and shifting means, placard detaining means, adapted to engage within said marginal recess to hold down a placard, means for initiating the separation of the placards successively, and placard transferring and reversing means. 100

8. In a display apparatus, the combination of a plurality of independent, flexible placards each provided with a dovetailed marginal recess, with supporting and shifting means, placard detaining means, adapted to engage within said marginal recess to hold down a placard, means for initiating the separation of the placards successively, and placard transferring and reversing means. 110

9. In a display apparatus, the combination of a plurality of independent, flexible placards each provided with a dovetailed marginal recess in each of two opposite edges, with supporting and shifting means, placard detaining means adapted to engage within the dovetailed marginal recesses to hold down the placards, means for initiating the separation of the placards successively, and placard transferring and reversing means. 120

10. In a display apparatus, the combina- 130

tion of a plurality of independent, flexible placards, with screw threaded supporting and shifting means and placard transferring means embodying a plurality of cooperating rollers.

11. In a display apparatus, the combination of a plurality of independent, flexible placards, with screw threaded supporting and shifting means and placard transferring means embodying a plurality of rollers and a cooperating flexible element.

12. In a display apparatus, the combination of a plurality of independent, flexible placards, with screw threaded supporting and shifting means and placard transferring means embodying a plurality of rollers and a plurality of cooperating flexible elements.

13. In a display apparatus, the combination of a plurality of independent, flexible placards, with screw threaded supporting and shifting means and placard transferring means embodying a plurality of cooperating rollers, and a plurality of belts cooperating therewith.

14. In a display apparatus, the combination of a plurality of independent, flexible placards, with screw threaded supporting and shifting means and placard transferring means embodying a plurality of cooperating rollers disposed in a plurality of horizontally parallel planes.

15. In a display apparatus, the combination of a plurality of independent, flexible placards, with screw threaded supporting and shifting means and placard curving and transferring means.

16. In a display apparatus, the combination of a plurality of independent, flexible placards, with screw threaded supporting and shifting means and means for transferring the placard edgewise in a curved course.

17. In a display apparatus, the combination of a plurality of independent, flexible placards, with screw threaded supporting and shifting means, placard transferring means and deflecting means.

18. In a display apparatus, the combination of a plurality of independent, flexible placards, with supporting and shifting means, means for raising, transferring from rear to front and lowering the placards successively and means for preliminarily arresting each placard when lowered.

19. In a display apparatus, the combination of a plurality of independent, flexible placards, with supporting and shifting

means, means for raising, transferring from rear to front and lowering the placards successively and means, embodying a retractable support, for preliminarily arresting each placard when lowered.

20. In a display apparatus, the combination of a plurality of independent, flexible placards, with supporting and shifting means, means for raising, transferring from rear to front and lowering the placards successively, and means, embodying a resilient, retractable support, for preliminarily arresting each placard when lowered.

21. In a display apparatus, the combination of a plurality of independent, flexible placards, with supporting and shifting means, means for raising, transferring from rear to front and lowering the placards successively and means, embodying an inclined 75 guide and a retractable support, for preliminarily arresting each placard when lowered.

22. In a display apparatus, the combination of a plurality of independent, flexible placards, with supporting and shifting means, means for raising, transferring from rear to front and lowering the placards successively and an inclined guide and a retractable support projecting therethrough for preliminarily arresting each placard 85 when lowered.

23. In a display apparatus, the combination of a plurality of independent, flexible placards, with supporting and shifting means, means for raising, transferring from rear to front, reversing and lowering the placards successively and means for preliminarily arresting each placard when lowered.

24. In a display apparatus, the combination of a plurality of independent, flexible 95 placards, with supporting and shifting means, means for raising, transferring from rear to front and lowering the placards successively and means, embodying a retractable support, means embodying cams for 100 retracting such support, for preliminarily arresting each placard when lowered.

25. In a display apparatus, the combination of a plurality of independent, flexible 105 placards, with worms constituting supporting and shifting means, eccentric separating means, raising, transferring, reversing and lowering means, arresting means, and automatic means for releasing the arresting means.

LESLIE R. McDONALD.
